GEORGE G. GOING, OF STAMFORD, CONNECTICUT, ASSIGNOR TO REMINGTON TYPE-WRITER COMPANY, OF ILION, NEW YORK, A CORPORATION OF NEW YORK

TYPEWRITING MACHINE

Application filed July 18, 1929. Serial No. 379,186.

My invention relates to ribbon reversing mechanism for typewriting and like machines, and more specifically to automatically operating means for shifting the switching mechanism from a neutral position where no feeding is effected to a ribbon feeding position, if for any reason such switching mechanism should be accidentally retained in the neutral position.

10 The main object of my invention, generally stated, is to provide simple and efficient mechanism of the character specified.

To the above and other ends which will hereinafter appear, my invention consists in 15 the features of construction, arrangements of parts and combinations of devices set forth in the following description and particularly pointed out in the accompanying claims.

In the drawings wherein like reference 20 characters designate corresponding parts in the different views:

Fig. 1 is a fragmentary top plan view of a typewriting machine with parts omitted, sufficient of the machine being shown to illustrate my invention in its embodiment 25 therein.

Fig. 2 is a fragmentary perspective view of certain of the parts shown in Fig. 1.

I have shown my invention, in the present 30 instance, embodied in a noiseless portable typewriting machine, the devices of the present invention co-acting with ribbon mechanism of the character disclosed in my application Serial #363,757, filed May 17, 1929.

35 From certain aspects of the present invention it may be regarded as an improvement on the construction disclosed in my said application with which it may be readily combined without modifying, or materially modifying the existing structural features thereof. However, it should be understood that the invention may be employed in combination with various forms of ribbon reversing mechanism and in typewriting and like machines 40 varying widely in character.

The ribbon reversing mechanism, as it is 45 illustrated in the present instance, comprises two ribbon spools 1 on which the ribbon 2 is wound and extends across the machine from spool to spool. The spools are supported in

suitable bearings on a casting 3 fixed at its ends to the side plates 4 of the machine frame. The lower flange 5 of each ribbon spool is fixed to a depending sleeve or hollow shaft 6 received within a bearing sleeve 7 supported on the casting 3. The lower end of each hollow shaft 6 has a ratchet wheel 8 attached thereto by a set screw 9 that is threaded into a tapped opening in the hub 10 of the ratchet wheel. A controlling member 11 is pivoted at 12 to the core 13 of each ribbon spool and has one arm that extends through a slot 14 in the core of the spool and against which the ribbon 2 wound on the spool bears. The other arm of the controlling member passes through the eye of a weighted interponent 15 contained within the associated hollow shaft 6 and adapted to move longitudinally from the ineffective full-line, to the effective dotted line position in Fig. 2. When in the last mentioned position the lower end of the interponent 15 will be below its companion ratchet wheel 8, and in the path of movement of a member 16 of the ribbon reversing mechanism, to effect a shifting of the reversing mechanism in a manner which will herein-after more clearly appear.

It will be understood that when the ribbon is exhausted from either ribbon spool, this will free its controlling member 11 permitting 80 the companion interponent 15 to drop to effective position. When on the other hand, ribbon is wound on either spool which may be exhausted, this shifts the companion controlling member 11 to the full line position 85 shown in Fig. 2 and lifts the associated interponent 15 to ineffective position within its hollow shaft 6.

The means by which each ratchet wheel 8 is turned, and by which the pawls that coact 90 with said ratchet wheels are shifted into and out of effective position will now be described.

The various printing key levers 17 extend over a universal bar 18 connected by arms 19 to a rock shaft 20 mounted at its ends to rock 95 on pivot screws 21 received in tapped openings in the side plates 4 of the machine frame. Fixed to and extending upwardly from the rock shaft 20 are two crank arms 22, each connected by a pull link 23 to an angular actu- 100

ating lever 24 pivoted at 25 to a shifting, switching or reversing member or bar 26. Said member 26 extends from side to side of the machine and is mounted for shifting movement in the direction of its length and transversely of the machine, as will herein-after more clearly appear.

Each angular actuating lever 24 carries two pawls 27 and 28 connected together by a spring 29 that tends to force the engaging nose of each pawl towards its companion ratchet wheel 8. Each pawl 27 is a holding pawl and each pawl 28 is a feed pawl, and the construction is such that one companion pair of pawls 27 and 28 will be out of engagement with the associated ratchet wheel when the other pawls are in engagement with their ratchet wheel, as shown in Fig. 1, and this depends on the position of the shifting member 26.

It will be seen that each pawl 27 is pivoted, as at 25, on the same pivotal center as the companion actuating lever 24, so that no movement is transmitted to the holding pawls during the operation of said levers, the active pawl 27 merely remaining in engagement with its wheel 8 to prevent a backward movement thereof. On the other hand each feed pawl 28 is pivoted at 30 to its actuating lever 24 to the rear of the pivot 25 thereof and will partake of the movement of its actuating lever to effect a feed of the associated wheel 8 when in engagement therewith.

Associated with each feed pawl 28 is a stop pin 31 projecting upward from the switching member 26. The relation of each stop pin 31 to its pawl 28 is such that when a pawl 28 engages its wheel 8 the companion stop pin 31 will be out of contact with the pawl, as shown at the left hand side of Fig. 1. When, however, the switching member 26 is shifted, the stop 31 of the active pawl 28 will engage it and carry it out of engagement with the associated ratchet wheel 8, as shown at the right hand side of Fig. 1. Each pawl 28 when thus shifted out of engagement is adapted to contact with the companion feed pawl 27 and carry it out of engagement with its wheel 8.

From what has been said it will be understood that each actuation of a printing key 17^a is effective through the universal bar 18, rock shaft 20, links 23 and levers 24 to actuate both pawls 28, to feed the ribbon in one direction or the other depending on which pawl 28 is the effective pawl.

The switching member 26, in the present instance, is in the nature of a sheet metal bar having upstanding ears 32 at the ends thereof. Each of these ears carries a pin 33 projecting outward therefrom through a bearing opening in a side plate 4 of the frame and extending beyond the outer face of such side plate. This provides means for supporting the switching or shifting bar 26 for endwise

movement, and also provides means whereby said bar may be shifted at will by the hands of the operator.

In order to assure a completion of the shifting movement of the bar 26 when started, and to prevent an accidental shifting of the bar from its shifted position, there is provided a detent spring 34 pivotally connected at one end to a fixed pin 35 and at its opposite end to a depending pin 36 on the bar 26. The force of this spring 34 is exerted in either one direction or the other on the bar 26 when its dead center position is passed, depending on the direction in which the bar is moved.

In effecting an automatic reversal in the direction of the feed of the ribbon, the interponent of the exhausted spool is dropped, as hereinbefore explained, into the path of the associated member 16 which constitutes the rear arm of the companion actuating lever 24. The pivotal movement of this lever 24 having thus been arrested or blocked by the companion interponent 15, the actuation of a printing key will tend to actuate said lever and the reactive force of such attempted operation of the lever will be exerted through its pivot 25 to shift the bar 26 to the left as the parts appear in Fig. 2, or to the right if the interponent 15 of the right hand spool is dropped. This will result in shifting the inactive pawls 27 and 28 into effective position and the effective pawls to ineffective position, thereby automatically reversing the direction of the feed of the ribbon, winding it on the empty spool and off of the full spool.

In addition to the foregoing mechanism there is provided on the rock shaft 20 an additional crank arm 37, which is connected to a link 38 suitably connected to a ribbon vibrator (not shown), as in my previously mentioned application, but which for the purposes of the present invention, it is unnecessary to disclose. The rock shaft 20 and the parts connected therewith are returned to normal position by a spring 39.

The mechanism thus far described is the same as that disclosed in my application hereinbefore referred to.

It has been found in practice that at times the shifting member 26 will be accidentally held in a centralized neutral position at which time both sets of pawls 27 and 28 remain ineffective, and as long as the machine remains in this condition there can be no feed of the ribbon. The operator may not observe this condition and imperfect work will result. This condition does not result, ordinarily, from any faulty operation of the reversing mechanism, whether the latter be actuated automatically or by hand. It results ordinarily from handling the machine. Thus, it is customary in moving the machine to place the hands on opposite sides thereof and lift it in this manner. This brings the

hands of the operator against the pins 33 which effects a shifting of the bar 26 to a centralized neutral position where it is held by the operator, the spring detent 5 34 at this time being dead centered or substantially dead centered. The operator then places the machine down at a convenient place where it is to be operated, without observing the condition of the machine and the 10 ribbon will not feed when the machine is operated.

Now in order to overcome the foregoing difficulty I have provided automatically operating means for shifting the ribbon reversing means from a central, neutral, or non-effective position to an effective ribbon feeding position in the event that, for any cause, such mechanism be accidentally stalled, left or held in such ineffective condition. I 20 believe that I am the first to have provided any such construction and wish to be understood as claiming the same broadly.

In the present embodiment of my invention, and in its application to the machine referred to, I have added a forwardly projecting extension 40 on the shiftable bar 26. This extension may be in the nature of a separate piece fixed to the bar 26, or may be formed integral therewith. The forward 30 end of this extension is beveled in opposite direction to provide two oppositely disposed cam faces or edges 41 meeting at a central point 42. An upwardly and rearwardly extending actuating member or arm 43 has its 35 U-shaped base 44 secured by a screw 45 to the rock shaft 20, which is angular in cross section. In this manner the arm 43 is fixed to rock with the shaft 20. The rear free end of the arm 43 is beveled at 46 where it is 40 adapted to coact with one or the other of the cam faces 41 under conditions which will presently appear. The relation of the parts is such that if the bar 26 be at one end or the other of its shifting movement, then the arm 45 43 will be clear of the cam faces 41 in its vibrating movement. If, however, the bar 26 for any reason becomes stalled or is held in its centered position, holding both sets of 50 pawls 27 and 28 out of operation, this will result in bringing and holding the point 42 substantially in alignment with the free end of the arm 43. In reaching this position it is necessary to cam the arm 43 forward against the force of the spring 39 where it may be 55 held by the extension 40 carrying the cams 41. At this time a depression of a printing key will result in rocking the arm 43 further forward and when pressure is released from the depressed printing key the reaction of the 60 spring 39 will cause the arm 43 to move rearward to normal position, and said arm acting on one or the other of the cam faces 41 will cause the bar 26 to be shifted either to right or left and bring one or the other of the two 65 sets of pawls 27, 28 into effective position.

One or more strokes of the printing keys will be effective to attain the end in question, usually two strokes will suffice, and sometimes one stroke. It is immaterial in which direction the bar 26 is shifted. If it happens, for example, to be shifted in a direction that will cause the ribbon to be fed off a spool that has just started to have the ribbon wound on it, then the automatic ribbon reverse will function as soon as the ribbon on such spool has been exhausted therefrom and it will be turned in the opposite direction to wind the ribbon on it again.

It will be understood that the devices of my invention are in the nature of safety devices or auxiliary controlling means that are used in addition to the ribbon reversing means and in combination therewith to assure an effective reversing operation in the event that the reversing means become stalled or are, for any reason accidentally held in the neutral or ineffective position.

From the foregoing description it will be seen that I have provided simple and effective means for attaining the ends pointed out and that such means may be readily applied to the machine and ribbon reversing mechanism referred to, without modifying, or materially modifying, the existing structural features thereof. It is again pointed out, nevertheless, that the invention is not limited to embodiment in such machine or to its combination with such mechanism, as it is capable of use in many machines that vary widely in construction. The invention is broadly 95 claimed herein and various changes may be made in the construction without departing from my invention as it is defined in the accompanying claims.

What I claim as new and desire to secure by Letters Patent, is:

1. The combination of ribbon-feeding and reversing mechanism, and automatically operating means for switching said mechanism to a ribbon-feeding condition only in the event that it becomes stalled in a neutral non-ribbon-feeding condition.

2. The combination of ribbon-feeding and reversing mechanism including a switching element for changing the direction of feed of the ribbon, and automatically operating means that are brought into use and operate on the switching element to move it to a ribbon-feeding position only in the event that said switching element becomes stalled 110 in a neutral non-ribbon-feeding position.

3. The combination of ribbon-feeding and reversing mechanism including a switching element for changing the direction of feed of the ribbon, and auxiliary automatically operating means including an actuating member operated at each actuation of a printing key and means for bringing said switching element into control of said actuating member for operation thereby only in the 125 130

event that said switching element becomes stalled in a neutral non-ribbon-feeding position.

4. The combination of ribbon-feeding and reversing mechanism including a switching element for changing the direction of feed of the ribbon, and automatically operating means including printing keys, an actuating member actuated at an operation of any 10 of said keys, a member connected with said switching member and brought into cooperative relation with said actuating member for a shifting of the switching member thereby only in the event that the switching member becomes stalled in a neutral non-ribbon-feeding position.

5. The combination of ribbon-feeding and reversing means including a switching element that is shifted in one direction or the 20 other and thereby determines the direction of the feed of the ribbon, and automatically operating means that are brought into use to shift said switching element to a ribbon feeding position only in the event that said 25 switching element becomes stalled in a neutral non-ribbon-feeding position, said automatically operating means including an actuating device that is operated at each actuation of any of the printing keys, and a cooperative device on the switching element that is brought into cooperative relation with said actuating device for actuation thereby by the 30 positioning of the switching element in such neutral position.

35. 6. The combination of ribbon-feeding and reversing means, and automatically operating auxiliary controlling means for shifting said reversing means to bring about a feed of the ribbon, said auxiliary means being 40 normally ineffective and rendered effective by a conditioning of the ribbon-feed and reversing means so that it is ineffective to feed the ribbon.

45. 7. The combination of ribbon-feeding and reversing means including a shiftable reversing member the position of which at one end or the other of its throw determines the direction of the feed of the ribbon and the intermediate positioning of which renders 50 the feed mechanism ineffective, and automatically operating auxiliary controlling means that are operative on said reversing member only when it is in said intermediate position at which time the auxiliary controlling means 55 are effective to shift the reversing member to an end of its throw and thereby render the ribbon-feed mechanism effective.

60. 8. The combination of ribbon-feeding and reversing means including a shiftable reversing member the position of which at one end or the other of its throw determines the direction of the feed of the ribbon and the intermediate positioning of which renders the feed mechanism ineffective, and automatically operating auxiliary controlling means that are 65

operative on said reversing member only when it is in said intermediate position at which time the auxiliary controlling means are effective to shift the reversing member to an end of its throw and thereby render the 70 ribbon feed mechanism effective, said auxiliary controlling means comprising a double face cam, a member that coacts therewith, and means controlled by each actuation of any of the printing keys to bring said cam and its 75 coacting member when they are in cooperative relation into use one on the other to effect a relative shifting movement between the two.

9. The combination of ribbon-feeding and reversing means including a shiftable reversing member the position of which at one end or the other of its throw determines the direction of the feed of the ribbon and the intermediate positioning of which renders the feed 80 mechanism ineffective, and automatically operating auxiliary controlling means that are operative on said reversing member only when it is in said intermediate position at which time the auxiliary controlling means 85 are effective to shift the reversing member to an end of its throw and thereby render the ribbon feed mechanism effective, said auxiliary controlling means comprising a double face cam on said reversing member, an actuating member cooperative with said cam when the reversing member is stalled in an intermediate position, and means controlled by an actuation of any of the printing keys 90 for operating said actuating member.

10. The combination of two ribbon spools, a ratchet wheel for each ribbon spool, a feed pawl for each ratchet wheel, means for actuating said pawls at the actuation of any printing key, shifting means for shifting one of said pawls into cooperation with its ratchet wheel when the other pawl is shifted out of cooperation with its ratchet wheel, said shifting means including a switching member 105 shiftable in one direction or the other to determine the direction of feed of the ribbon, and automatically operating auxiliary shifting means operative on said switching member to shift it only when the switching member is stalled in an intermediate position and both feed pawls are maintained out of cooperation with their ratchet wheels.

11. The combination of two ribbon spools, a ratchet wheel for each ribbon spool, a feed pawl for each ratchet wheel, means for actuating said pawls at the actuation of any printing key, shifting means for shifting one of said pawls into cooperation with its ratchet wheel when the other pawl is shifted out of cooperation with its ratchet wheel, said shifting means including a switching member 120 shiftable in one direction or the other to determine the direction of feed of the ribbon, and automatically operating auxiliary shifting means operative on said switching member 125 shiftable in one direction or the other to determine the direction of feed of the ribbon, and automatically operating auxiliary shifting means operative on said switching mem- 130

ber to shift it only when the switching member is stalled in an intermediate position and both feed pawls are maintained out of cooperation with their ratchet wheels, said auxiliary shifting means comprising a double cam on the shifting member, an actuating member cooperating therewith, and means controlled by an actuation of any of the printing keys for operating said actuating member.

12. The combination of two ribbon spools, a ratchet wheel for each ribbon spool, a feed pawl for each ratchet wheel, means for actuating said pawls at the actuation of any printing key, shifting means for shifting one of said pawls into cooperation with its ratchet wheel when the other pawl is shifted out of cooperation with its ratchet wheel, said shifting means including a switching member shiftable in one direction or the other to determine the direction of feed of the ribbon, and automatically operating auxiliary shifting means operative on said switching member to shift it only when the switching member is stalled in an intermediate position and both feed pawls are maintained out of cooperation with their ratchet wheels, said auxiliary shifting means comprising a double cam on the shifting member, and an automatically operated actuating member with which said cam is brought into cooperative relation only when said shifting member is stalled in an intermediate position where the actuating member is effective on the cam to shift said shifting member and assure a feed of the ribbon.

13. The combination of two ribbon spools, a ratchet wheel for each ribbon spool, a feed pawl for each ratchet wheel, means for actuating said pawls at the actuation of any printing key, shifting means for shifting one of said pawls into cooperation with its ratchet wheel when the other pawl is shifted out of cooperation with its ratchet wheel, said shifting means including a switching member shiftable in one direction or the other to determine the direction of feed of the ribbon, and automatically operating auxiliary shifting means operative on said switching member to shift it only when the switching member is stalled in an intermediate position and both feed pawls are maintained out of cooperation with their ratchet wheels, said auxiliary shifting means comprising a double cam on the shifting member, an automatically operating actuating member with which said cam is brought into cooperative relation only when said shifting member is stalled in an intermediate position where the actuating member is effective on the cam to shift said shifting member and assure a feed of the ribbon, and means controlled by an actuation of any of the printing keys for actuating said actuating member.

14. The combination of ribbon-feeding and

reversing mechanism, and automatically operating auxiliary shifting mechanism operative on said reversing mechanism to shift it only in the event that it is stalled in a position where the ribbon-feed mechanism is rendered ineffective, said auxiliary shifting mechanism being ineffective on the reversing mechanism at any other time.

15. The combination of ribbon-feeding and reversing mechanism, and automatically operating auxiliary shifting mechanism operative on said reversing mechanism to shift it only in the event that it is stalled in a position where the ribbon-feed mechanism is rendered ineffective, said auxiliary shifting mechanism comprising a double cam carried by a part of the reversing mechanism, an actuating member cooperative with said cam, a rock shaft which carries said actuating member, a universal bar connected with and rocking said shaft, and printing key levers operative on said universal bar.

16. The combination of two ribbon spools, a ratchet wheel for each ribbon spool, a feed pawl for each ratchet wheel, means for actuating said pawls at the actuation of any printing key, shifting means for shifting one of said pawls into cooperation with its ratchet wheel when the other pawl is shifted out of cooperation with its ratchet wheel, said shifting means including a switching member shiftable in one direction or the other to determine the direction of feed of the ribbon, means operable at will by hand for shifting said switching member, automatically operating means for shifting said switching member when an end of the ribbon is reached, and automatically operating auxiliary shifting means operative on said switching member to shift it only when the switching member is stalled in an intermediate position and both feed pawls are maintained out of cooperation with their ratchet wheels.

17. The combination with ribbon feed and reversing mechanism including means for automatically reversing the direction of the feed of the ribbon when an end thereof is reached and also including hand actuated means that enable the direction of the feed of the ribbon to be reversed at will, of auxiliary automatically operating shifting means operative on said ribbon reversing mechanism only in the event that it becomes stalled in a position where the ribbon feed mechanism is rendered ineffective through the accidental handling of the said hand actuated means or for any other reason, said auxiliary shifting means being ineffective on the reversing mechanism at any other time.

Signed at Stamford, in the county of Fairfield and State of Connecticut, this 17th day of July, A. D. 1929.

GEORGE G. GOING.
